GAS CIGARETTE LIGHTER

Zenzaburo Yoshino, Tokyo, Japan, assignor to Zenza Bronica Kogyo Kabushiki Kaisha, Tokyo, Japan

Filed Dec. 12, 1966, Ser. No. 5,001

Claims priority, application Japan, June 14, 1966

Term of patent 3½ years

(Cl. D48—27)

Fig. 1

Fig. 3

Fig. 2

Fig. 4

Fig. 6

FIG. 1 is a plan view;
FIG. 2 is a front view;
FIG. 3 is a left side view;
FIG. 4 is a right side view;
FIG. 5 is a bottom view; and
FIG. 6 is a perspective view.

In FIGS. 2, 5 and 6, the oblique lined rectangular portions represent transparent window plates; the Z-shaped feature in FIGS. 2 and 6, and the rectangular shaped feature in FIGS. 3 and 6 represent openings. The side opposite FIG. 2 is the same in appearance as the side shown.

I claim:

The ornamental design for a gas cigarette lighter, substantially as shown and described.
